PAIR OF SPECTACLES

Irene Gayson, New Britain, Conn.

Application July 29, 1949, Serial No. 4,195

Term of patent 14 years

(Cl. D57—1)

To all whom it may concern:

Be it known that I, Irene Gayson, a citizen of the United States, residing in New Britain, county of Hartford, and State of Connecticut, have invented a new, original, and ornamental Design for a Pair of Spectacles, of which the following is a specification, reference being had to the accompanying drawing, forming part thereof.

Fig. 1 is a front elevation of a pair of spectacles, showing my new and ornamental design.

Fig. 2 is a rear view of the same.

Fig. 3 is a side view of the same.

I claim:

The ornamental design for a pair of spectacles, substantially as shown.

IRENE GAYSON.
